WIRE COATING PROCESS AND APPARATUS

Randall W. Schultz, Williamsport, Pa., assignor
to Metalloys Company, Williamsport, Pa., a
corporation of Pennsylvania

Application August 13, 1936, Serial No. 95,939

10 Claims. (Cl. 22—57.2)

In applying protective metallic coatings, such as zinc, lead, tin, cadmium, aluminum, etc., to other metal articles, such as wire, bars, strips, etc., it is very desirable to have the coating as 5 pure as possible and unalloyed with the metal of the coated article. It is also desirable to control the thickness, or weight, of the coating. In some cases it is also desirable to have a coating that is very heavy, and this is practically impossible with 10 present commercial methods of applying protective coatings.

In the field of work to which my invention applies; namely, the coating of wire, rods, bars, strips, etc., the two most generally used processes 15 are electrical deposition and the "hot dip" process. The former is used to only a very limited extent, due to the slowness of the operation and the consequent cost of the process. The "hot dip" process is the one most generally employed in commercial practice; but as this is performed at the 20 present time, it has some very serious drawbacks.

It is impossible to obtain a relatively thick pure coating of one metal on another by the "hot dip" process. This can be readily understood once this 25 process is carefully analyzed. In any "hot dip" process the thickness, or weight, of the coating is a function of the time of immersion, and the temperature of the coating bath. The actual process of coating proceeds gradually and in no case is 30 the applied coating of pure metal throughout the entire thickness of the coating. Upon first entering a bath of coating metal, the article to be coated, for instance, a steel wire, is brought up to nearly the same temperature as the coating bath.

As the outer surface of the wire reaches the 35 temperature of the coating bath, the coating metal gradually penetrates and alloys with the base or coated metal. As the temperature of the bath gradually penetrates into the metal which is being 40 coated, the alloy penetration proceeds likewise, and the total depth of the penetration depends principally on the time the article being coated is submerged. Such a coating, analysis shows, is not of pure coating metal throughout 45 the thickness of the coating, but is an alloy, ranging in composition gradually from base metal within to substantially pure coating metal without. The inner portion of the coating will be preponderantly of the base metal, but the composition will change gradually until, at the outer 50 surface, the coating will be found to be a "skin" of practically pure coating metal.

In some cases, the coating applied by the hot-dip process is very unsatisfactory. For instance, 55 where the coated article is subject to corrosion,

because its resistance to chemical action is weakened by the fact that the alloy will not withstand attack by corrosion as well as the pure coating metal. Again in some cases, where the coated article is continually being bent or twisted, as for 5 instance in steel wire rope, the alloy formed by the "hot dip" process will spall or crack off from the coated article, due to the fact that the alloy formed from the base metal and the coating metal is in all cases much harder and more brittle 10 than the pure coating metal.

Numerous attempts have been made to improve the hot process method of applying protective coatings. Most of these have used dies in one form or another to flow the coating metal on to 15 the article being coated. These past attempts have not been entirely successful. In some cases, it had been impossible to apply the coating uniformly and evenly, especially on round wire, as the wire could not be accurately centered in the 20 coating die. However, the main reason for failure when using dies has been due to the coating metal oxidizing in the die. It is a well known fact that metals, such as tin, zinc, lead, etc., which are mostly used as protective coatings for other 25 metals, oxidize and rapidly form dross at the temperature used. This accumulates on the die and around the orifice thereof, and interferes with the coating by reducing the effective size of the orifice 30 therein.

The object of my invention is to coat objects of the character specified by casting the coating metal in a die around the wire, bar, strip, or other form, either directly or by means of an intermediate coating; the coating being effected under 35 such condition that oxidation, and the consequent formation of dross is practically or entirely avoided.

This invention involves a method or process for accomplishing the result stated; and a mechanism or apparatus for carrying out the method or process. Broadly stated, the method involves the removal of air from about the casting die, and the drawing of the metal through the die around the article being coated, thus making impossible 45 the oxidization referred to, and at the same time producing an easier and more uniform flow of metal through the casting die than is possible with any pressure system of casting. The machine or apparatus comprises means by which the suction, and consequent removal of air from 50 around the die, and flow of the coating metal, is effected.

I have illustrated the best means for practicing 55 my invention, as it would be applied to the coat-

ing of round wires, but the invention is not limited to the coating of wires, and the character of the dies and other features will be determined by the shape of the article to be coated.

- 5 In the drawings:
 Fig. 1 is a side elevation of the coating machine or apparatus and winding reels, for receiving the coated wire.
 Fig. 2 is a sectional view on the line 2—2, Fig. 10 1, looking in the direction of the arrows.
 Fig. 3 is a sectional view on the line 3—3, Fig. 2, likewise looking in the direction of the arrows.
 Fig. 4 is an end elevation partly broken away, of the coating machine.
 Fig. 5 is a plan view of the coating machine, likewise partly broken away.
 Fig. 6 is an enlarged partial sectional view on the line 6—6, Fig. 5, looking in the direction of the arrows.
 Fig. 7 is a partial sectional view on the line 7—7, Fig. 6, and showing particularly the valves by which the flow of molten metal to the casting dies is controlled.
 Fig. 8 is a sectional view on the line 8—8 Fig. 6, and looking in the direction of the arrows.
 Fig. 9 is a sectional view on the line 9—9, Fig. 8, and showing the ejector in section.
 Fig. 10 is a sectional view on the line 10—10, Fig. 7, and showing the die holder in section.
 Fig. 11 is an enlarged view of the die holder, dies and associated parts of Fig. 10.
 Fig. 12 is a detail view of the pump used to supply the ejector.
 Generally speaking, the wire, or the other object to be coated, is first thoroughly cleansed, then passed through a preheating and preliminary coating bath, and then, while still hot, passed directly to the die casting devices, at which point the final coating metal is applied around the moving wire. The coated wire is then immediately cooled and wound on spools or otherwise disposed of.
 As here disclosed, the suction or vacuum forming device is an ejector, through which oil, water or other suitable fluid is forced around the die. This not only removes the air from around the die, and produces the necessary vacuum, but also cools the coated wire as it emerges from the die. Of course, any other suitable vacuum producing means may be used.
 As here illustrated, the mechanism or apparatus is provided with means for simultaneously coating four separate wires; but since each set of elements is a duplicate of the others, a description of one will suffice for all.
 In the accompanying drawings, to which reference is here made, the wire or other shape to be coated 10 is taken from any suitable source as a reel (not shown). It is first passed through a fluxing bath 11, Fig. 1, beneath a roller or other guide 12, beneath a wiper guide 13 and then between rollers 14. As the wire passes through the flux, the surface is cleansed and prepared for further operations.
 From this fluxing bath, in the apparatus here disclosed, the wire is passed through an opening 15 into a bath 16 of some preliminary coating metal and out through a similar opening 15'. This bath may be the same metal as that which forms the final coating, as lead, where the final coating is of that metal; or it may be some metal which will form a true alloying bond between the wire and the metal of the final coating. This bath 16 is contained in a suitable tank 17, which is thoroughly heat insulated, as by the same non-

heat-conducting body 18, which in turn is retained in some suitable casing 19. This bath is heated in any suitable way, as by electric heating units 20, Fig. 2. Any sufficient number of these heaters may be used.

Each of the several tanks 17 is provided with a cover 21 Fig. 2, hinged in any suitable manner, as to the casing 19. These covers 21 are shown best in Fig. 2, where the one on the left is illustrated as raised and the others as closed. Within the several tanks 17, the wires 10 to be coated pass through suitable guides 22 and 23. Of these, in the apparatus here shown, 22 are stationary, while 23 are carried by the covers 21, and are adapted to be raised and lowered with the raising and lowering of the covers. When in the lower position, the wires are held depressed in the molten metal. Any suitable arrangement of guides may be used, it merely being important that the wires shall be held down in the mass of molten metal.

A wiper 24, one for each tank, removes excess molten metal from the wire as it passes out of the tank through the outlet 15' to the final coating devices. 25

The purpose of this bath is to bring the wire 10 to the temperature necessary for the final coating; and also in some cases, to coat the surface of the wire with an intermediate coating of metal, which metal may be a mere preliminary coating of the metal used for the final coating, or a bonding metal which will alloy with both the base and the final coating. So far, the practice is that usually followed in the "hot dip" process of coating. 30 35

Final coating

The metal to be applied as the final coating is contained in a pot or kettle 25, Fig. 4, which is heated to the desired temperature in any suitable way, as by one or more electric heating elements 26, Fig. 5. This type of heater is immersed directly in the metal being heated; and is supplied with current through suitable connections, as by terminals 27, Fig. 5. The pot or kettle 25 is provided with an opening 28 in the bottom thereof, Fig. 5, through which the coating metal can flow to the casting dies. As here shown, the molten metal flows into the pipe or tube 29, Fig. 4, and thence into a horizontal manifold 30, Fig. 4, to the die casting blocks 31, one of which is provided for each wire to be coated. One or more electric heaters 26', having terminals 27' extend through the manifold 30 so as to keep the metal therein in fluid condition.

The melting pot 25 is sufficiently elevated above the manifold 30 and die blocks 31 to maintain a satisfactory head or pressure of metal in these parts; but, as will be described below, the flow of metal is not dependent on the head thus produced. 60

The melting pot 25 is surrounded by any suitable heat insulating material 32, enclosed in an outer casing 33. A suitable insulating cover 34 closes the top of this pot 25.

The machine or apparatus here illustrated employs only one melting pot for all of the several casting devices; but of course one such pot could be supplied for each die head 31 if desired. 65

Casting devices.—Each die head 31 is provided with a passage 35, Fig. 7, leading to a valve chamber 36. This passage is controlled by valve 37, which cooperates with a valve seat 38. This valve may be operated in any suitable manner, as by handle 39 on the valve stem 40, threaded into 75

a nut 41 which compresses packing 42 around the valve stem. The flow of metal from the manifold to the valve chamber 36 is controlled by opening and closing this valve.

5 A casting die proper 44 having an orifice 45 together with its cooperating elements, is mounted in each die head 31. Each head is bored to form a recess 43 threaded at 46, and shouldered at 47, Fig. 10. Within this recess is mounted a 10 plug 48 threaded to cooperate with the threads 46 of the die head 31, and provided with a ledge to rest on the shoulder 47 of the die head. The plug 48 is provided with a tapered opening 49 in which a die holder 50 is positioned. This opening 49 is closed by a cap 51 having an opening 52 which is threaded into the upper end thereof.

In order that liquid metal may pass from the valve chamber 36 to the casting die 44, the bore 43 in the head 31 is arranged so as to 20 intersect the valve chamber 36 at the point 53, thus forming a communicating passage at this point. The plug 48 is provided with an outer annular channel 54, which registers with this opening 53, and an inner annular channel 55 25 communicating with the outer channel 54 through passages 56 between them.

The plug 48 is threaded and is screwed into the recess 43. This threaded connection forms a 30 sufficiently tight seal at this point, and the ledge at the lower end of the plug rests on the seat 47, thus forming a seal at this point.

As before stated, the die 44 applies the outer coating to the wire. The wire to be coated must be kept central of this die, so that the coating 35 shall be of uniform thickness. In order to accomplish this, centering guides or dies are employed. In the apparatus here shown, two such dies are used, an upper one 57 having an orifice 58, and a lower one 59. This die has an elongation or projection on its underside in which the 40 orifice 60 is located, thus making it possible to bring this opening close to and directly above the center of the casting die 44, Figs. 10 and 11.

In order to aline these guiding dies with the casting die 44 and hold them in position with respect to each other, they are all enclosed in a sleeve 50, before referred to, tapered to fit more or less closely the tapered opening 49 of plug 48. This die sleeve has formed in its upper portion a series of slots 62 extending from at or near the 45 top to near the bottom thereof; and the lower part of this sleeve is shaped to fit closely into the bottom of the tapered opening 49, and rests on a seat 63, in the bottom thereof, which is cut away at 64. As here shown, the casting die 44 50 is placed in the bottom of the sleeve, and rests upon the annular ledge 65. In the lower part of the sleeve, directly above the die 44, a spacing ring 66 is inserted. The lower guiding die 59 55 rests upon the spacing ring 66. Directly above the die 59 is another spacing ring 68, which is somewhat longer than the lower spacing ring 66; and directly above this second spacing ring 68 is another guiding die 57 having therein an orifice 58. These elements are all enclosed in the 60 die holder 48, the casting die 44 resting on the ledge 65 in the bottom thereof, the lower spacing ring 66 resting on the die 44, the lower guiding die 59 resting on the lower spacer 66, and the second and longer spacing ring 68 resting on 65 the guiding die 59 and the upper guiding die 57 resting on the spacer 68. The upper guiding die 57 is seated in the screw cap 51, which cap contains a ledge 70. By turning down this cap 51, the ledge 70 will press on the top of the upper guiding die 57, and pressure will thus be transmitted 70

through the spacer 68, lower centering die 59, and lower spacing ring 66, to the casting die 44, which is thereby forced to its seat 65. This arrangement forms a construction which is quickly assembled, and easily disassembled for inspection, replacement of parts, or repair. 5

In practice, it is desirable that the wire to be coated shall pass through the coating metal, and also that coating metal shall be supplied directly above the casting die. To supply the molten metal freely, the upper spacing ring 68, is provided with slots 71, through which molten metal can flow to the interior of the die holder and the lower spacing ring 66 with slots 72 through which molten metal can flow directly to the casting 15 die 44.

This arrangement of dies, and means for supplying molten metal thereto, has certain important advantages over the prior art. The guiding die 59 in effect divides the die chamber into two 20 parts, one above the die 59 through which the wire passes for a relatively long distance through the molten metal, and one between the guiding die 59 and the casting die 44, which is relatively short. From the casting die 44 the coated wire 25 passes directly to the cooling or quenching position to be hereafter described. This arrangement gives the coating time to be thoroughly alloyed with the surface of the wire while passing through the fluid metal above the die 59, but gives 30 very little time for this alloy to mix with the final coating metal as it is applied by the die 44. The result is a particularly pure final coating of the coating metal.

This long upper chamber in the ring or sleeve 35 68 also tends to permit the temperature of the wire to be raised to the temperature of the coating metal, as it passes therethrough, thus causing the final coating from die 44 to flow more freely around the wire. 40

In order to maintain the casting die and its associated elements at sufficient temperature to maintain the casting metal liquid, each die head is provided with a heating means. Such a heater is shown at 75, Figs. 6 and 10. As there illustrated these heaters are electrical resistance units of ring form, which rest, one in a recess 76 in each die head 31. Each heater is enclosed by a heat insulating ring 77, which ring is retained in place by other heat insulating rings 78 and 79, 50 which are secured to the die head by suitable screws 80, or by any other suitable means. Suitable leads 81, only one of which is shown, Fig. 6, are used to conduct current to these heaters.

Supported on or adjacent to each of the die 55 heads 31 is a grooved wheel 85, having its upper face in line with the outlet 15' of the preheating or preliminary coating chamber, and its vertical face in line with the orifice in the guiding die 57, Fig. 6. This wheel is mounted for rotation in any suitable way, as by support 86 bolted to an extension 87 of the die head. A protective casing 88 covers the wheel, and protects the wire and prevents undue radiation. The wire will thus be directed from the preheating or preliminary 60 coating tank directly to the center of the upper guiding die 57. And since the support for the wheel is mounted directly on the die head, the parts will not be subjected to displacement due to expansion and contraction of the parts. 65

Prior efforts to apply protective coatings to wire by the use of casting dies have involved difficulties. These troubles have been two-fold. First, where hydrostatic pressure alone, such as that caused by elevating the coating metal sup- 75

ply, is used to cause a flow through the casting die, the coating is apparently affected by the friction and eddies of the coating metal in the ducts leading to the die opening, such as the manifold 30 and passage 35, in the drawings of this application. The flow of coating metal through such passages apparently is not continuous and uniform, and this results in thin spots, or rings, in the coating on the wire. The second trouble 10 has been the oxidizing of the coating metal on the outgoing face of the coating die. Such oxidizing is particularly true where lead is used as the coating metal. This oxide, accumulating on the surface of the die, as for instance on the lower face of the die 44, finally protrudes over the opening in the die through which the wire passes, thus in effect reducing the size of such opening. When this happens the thickness of the coating being applied is reduced. Eventually 20 this oxide accumulation will close off the opening in the die, and act as a wipe on the wire, thus preventing any coating from being applied.

In my early experiments, attempts were made to solve these difficulties; first, by the use of increased hydrostatic pressures, and, second, by the use of a non-oxidizing agent around the casting die, or by a combination of the two. None of these means were successful. The use of a reduced atmosphere, or other non-oxidizing agent, 30 around the casting die will prevent an accumulation of oxide, and thus allow long use of the casting die without reduction in thickness of the coating on the wire, but even in such cases, and where relatively high hydrostatic pressures were 35 used, the thin spots, or rings, were still apparent. These thin spots, or rings, which appear on the wire at very regular and uniform distances apart, are apparently due to the fact that the pressure on the coating metal applied above the die causes 40 eddy currents in the flow, especially where the coating metal, in flowing to the die opening, passes sharp corners or bends in the manifolds. While the above is believed the cause of the imperfections noted, it is to be understood that the 45 effect may have been produced in other ways.

In my invention, I overcome these difficulties by means to be now described. It is a well-known fact that flow of a fluid caused by induction is much more steady and uniform than a forced 50 flow. This principle has been applied and used in my invention. This is done by creating a vacuum or partial vacuum at the outer face of the casting die which accomplishes two things: first, by reducing the atmospheric pressure on the 55 outer face of die 44, the coating metal is induced to flow through the opening 45, and, second, by creating a vacuum at this point, the formation of oxide is automatically prevented.

My experiments have definitely proved that the 60 flow of coating metal through the casting die and around the wire, caused by creating a vacuum at the outer surface of die 44, is much smoother and more uniform than a flow from hydrostatic pressure alone, and that the thin spots, or rings, 65 disappear when this method is used. Further than this, the fact that oxide formation is effectively prevented, allows the coating to be applied continuously, evenly, and uniformly for long periods of time.

70 While any suitable means for producing a vacuum may be used, that here shown is of the ejector type; that is, the type in which streams of water, oil or other liquid or gas, are caused to converge in a restricted passage and entrain the 75 surrounding air thus producing a vacuum, or at

least a partial vacuum, around the die and within the die holder. This particular type is well suited for this use as the stream of liquid, or gas, flowing through the diffusor part 113 is used as the cooling or quenching medium to quench the coating applied to the wire by the casting die. 5

While some hydrostatic pressure is used in the form of my invention here disclosed to create a flow of coating metal from pot 25, to and through opening 45 in die 44, such pressure is not necessary, as flow of coating metal can be induced by the vacuum means alone. 10

The speed at which coatings can be applied to wire is related to the pressure used on the coating metal, within certain limits; the higher the 15 pressure on the coating metal, the faster the wire can be passed through the casting die. In order to relieve the ejector of the necessity of inducing the flow through the different passages and manifolds, sufficient hydrostatic head is used to force 20 the coating metal through these passages and up to the opening 45 in die 44. This allows the vacuum produced to work more effectively in smoothing out the flow, and also secures a higher 25 speed of operation, without having the vacuum means unduly large.

Some flexibility in the apparatus is desirable. The delivery of coating metal to the casting die is dependent upon the static head of the metal and the vacuum produced by the suction device. As 30 it is more practical to vary the vacuum than it is to vary the head of molten metal, I have provided means for varying the flow of the coating metal by varying the vacuum produced by the ejector. By increasing the flow of liquid through the 35 ejector, the vacuum is raised and the flow of coating metal increased; by decreasing the flow, the vacuum is lowered and the flow decreased. Therefore, the amount of vacuum produced may be varied at will by varying the flow of fluid to 40 the ejector.

The ejectors as a whole are indicated by the character 90, Figs. 4 and 6, and the pump for supplying the liquid thereto by 91 Fig. 1. Only one pump is here used, but of course there is one 45 ejector for each die, and there may be a pump and ejector for each die. A pipe 92 having therein an accumulating reservoir 92' leads from the pump to the several ejectors, and the water or other fluid which passes through the ejectors is 50 received in any suitable reservoir as 93, whence it is returned to the pump.

The pump 91 is provided with a relief valve 106 actuated by spring 107. Pressure on this spring is supplied by nut 108, which screws into the extended portion 109 of pump 91. This construction is standard commercial practice and needs no further description. 55

The structure of the ejectors is shown in connection with the other elements of the apparatus 60 in Figs. 4 and 6. The ejector may be attached to its casting head 31 in any convenient way. As here shown, it is attached directly to the heat insulating ring 79, Fig. 10, by means of a metallic ring 94, which in turn is secured to the insulating 65 ring 79 by means of screws 95. This ring 94 is internally threaded at 96, Fig. 9, and the body 97 of the ejector is threaded at its upper end and engages with the thread 96 of the plate 94. A seal between the casing 97 and the ring 94 is 70 effected by the edge 98 on the body 97 engaging with the inner surface of ring 94.

The body 97 of the ejector is provided with two chambers, an upper one 99 in the form of an annulus, which communicates with the supply pipe 75

92, and a lower and larger one 100, which communicates with the die chamber through openings 101, and the openings in the rings 78 and 79, Figs. 8 and 9. A cone-shaped member 102, 5 connects the two chambers 99 and 100, and through the body of this cone is bored a series of holes 103 at an angle to the vertical, so that they converge at a point a short distance below the lower end of the cone.

10 The top of the chamber 99 is closed by a plug 103 having a screw threaded extension 104, by which it engages with a cooperating threaded portion of the nozzle 102. A flange 105 extends over the top of the upper chamber 99 and rests 15 upon the top of a casing 97, so that when the plug is screwed into its seat it will close the top of the chamber 99 with a tight fit. The two chambers 99 and 100, are connected only by the holes 103 in the cone 102.

15 Secured to the ejector body 97, and forming one of the essential parts of ejector, is a diffuser or nozzle. This diffuser consists of an upper funnel-shaped member 111, a middle screw threaded section 112, and a lower flaring member 25 113. The screw threaded portion 111 is adapted to be threaded into the opening 114 of the body 97, a flange 115 serving to form a tight joint with the bottom of the body 97. The upper funnel-shaped member 111 partly surrounds the cone 102, and the lower flaring member 113 joins with 30 the funnel at a constricted point or throat 116. This construction forms two channels through the ejector; one through 117 in the plug 103, and down through the central passage in the cone 102; the other from the die chamber, through the 35 openings 101, into chamber 100, and through the channel 118 between the cone 102 and the funnel 111.

40 The wire which is being coated passes from the coating die 50, directly down through the opening 117 in the plug 103, and on through the throat 116 of the ejector, and out through the nozzle 113.

45 At the throat 116 the wire is caught in the stream of water or other liquid that is now flowing through the diagonal openings 103, and is quenched or cooled at this point. From here it passes out to suitable winding mechanism, illustrated diagrammatically in Fig. 2, where the wire is shown passing under a guide wheel 121, to 50 winding drums 122, driven by any suitable means, as by a motor 123 and gearing 124.

Operation

55 The general operation of the several features has been given in describing the various parts of the machine or apparatus, but a general review of the complete operation may be helpful. The wire is here shown as first passing through the cleansing bath 11, and then through the preheating and preliminary coating bath 16. In this bath the wire is heated to approximately the temperature of the coating medium. While 60 in this heated condition it passes directly to the coating die. However, it is to be understood that previously coated wire may be used and be passed directly to the coating dies; or an uncoated wire may be passed directly thereto, as the circumstances justify. But whatever the 65 condition of the wire, it is desirable to have the temperature raised to approximately that of the coating metal before it passes through the coating die.

70 Assuming that the coating metal has been raised to the proper temperature, and that the die heads have been properly heated, the valves

36 for as many of the dies as are to be used are opened, and the die head and die chamber filled with liquid metal.

75 The valves 26 having been opened, the pump 91 started, the oil or water therefrom is discharged through the openings 103 in the cone 102. These liquid streams converge in the throat 116 of the ejector, and out of the nozzles 113, to the receiving tank 93, from whence it is returned to the pump.

10 The passage of the liquid through the ejector entraps the air in the die chamber and removes some of the same therefrom. The ejector thus produces a vacuum, or at least greatly lowers the air pressure, in the die chamber and prevents the introduction of new air thereto; and this effectively prevents the formation of oxide on the face of, and the vicinity of the die, thus making the formation of objectionable oxide impossible.

15 The formation of the vacuum at this point causes the liquid coating metal to flow from the melting pot, through the channels, around the dies, and finally through the casting die itself. The coating metal, as it is drawn through the 25 die 44, unites with the wire or with the preliminary coating on the wire, and solidifies around the wire now moving through the ejector. And as the heated metal reaches the point where the liquid streams unite, it is quenched and cooled. 30 The wire with coating now cast thereon then passes out of the machine to be disposed of as desired; it is here shown as received on spools or drums 122.

35 What I claim as my invention is:

1. The process of coating an elongated metal article of uniform cross section with a protective coating of another metal which comprises, moving the article to be coated through a casting die, simultaneously drawing molten coating metal 40 through the die around the article to be coated by reducing the atmospheric pressure beneath the die, and quenching the coated article.

2. The process of coating an elongated metal article of uniform cross section with a protective coating of another metal which comprises, moving the article to be coated through a casting die, removing the air from around the casting die to prevent oxidation and reducing the atmospheric pressure beneath the die so as to draw 45 molten coating metal through the die around the article being coated.

3. The process of coating an elongated metal article of uniform cross section with a protective coating of another metal which comprises moving the article to be coated through a casting die, drawing molten coating metal through the die around the article being coated, and simultaneously removing the air from around the die to prevent oxidation by means of a partial vacuum 55 beneath the die, and quenching the article being coated in the vacuum producing means.

4. In a machine for coating elongated metal articles of uniform cross section, the combination of a casting die, means for moving the article to be coated through the die, a source of molten metal, vacuum producing means for drawing the air from beneath the casting die and for drawing the molten metal through the die around the article to be coated, and means for passing 60 the coated article through the vacuum producing means to quench and cool the same.

5. In a wire coating machine, a die chamber, a casting die therein, means for supplying molten metal thereto, guides for keeping the wire 65

- central of the casting die, a fluid ejector connected to the die chamber for withdrawing air from around the casting die and to simultaneously draw the molten metal through the casting die, and means for passing the coated wire through the fluid of the ejector to cool the same.
5. In a wire coating machine, the combination of a die chamber, a casting die therein, a source of molten metal to supply the casting die, a fluid actuated ejector for drawing air from around the casting die so as to prevent oxidation of the coating metal on the die and for drawing the molten metal through the casting die around the wire, and means for passing the coated wire through the stream of fluid from the ejector to cool and quench the freshly coated wire.
10. In a wire coating machine, the combination of a die chamber, a casting die therein, means for passing a wire to be coated through the casting die, a liquid operated ejector in substantial alignment with the die chamber for withdrawing air from the die chamber and from around the casting die and for drawing molten metal through the die around the wire, and means for drawing the coated wire through the liquid which operates the ejector to quench and cool the freshly coated wire.
15. In a wire coating machine, the combination

tion of a die chamber, a die holder in the die chamber, a casting die in the lower part of the die holder, a guiding and centering die in the die holder dividing the same into an upper chamber of considerable length and a relatively short lower chamber, means for supplying molten metal to both chambers, and means for passing a wire to be coated first through the upper and longer chamber and then through the relatively short chamber and through the casting die.

10

9. In a wire coating machine, the combination of a die chamber, a die holder in the die chamber, a casting die in the lower part of the die holder, a guiding and centering die in the die holder dividing the die holder into an upper 15 alloying chamber and a lower casting chamber.

10. In a wire coating machine, a die assembly comprising a die plug having an opening therein, a die holder in the plug, a casting die in the lower part of the die holder, a guiding die spaced 20 from the casting die, a ring spacer resting on the guiding die, an entering guide resting on the ring spacer, a cap resting on the entering guide and cooperating with the opening in the die plug to hold the other elements of the die assembly in position.
